[57] CLAIM

The ornamental design for a head band hearing protector, as shown and described.

DESCRIPTION

FIG. 1 is a perspective view of a head band hearing protector showing my new design.

FIG. 2 is a side elevational view thereof, the opposite side elevational view being identical thereto;

FIG. 3 is a top plan view thereof;

FIG. 4 is a bottom plan view thereof;

FIG. 5 is a front elevational view thereof, the rear elevational view being identical thereto;

FIG. 6 is a cross sectional view thereof taken along line 6—6 of FIG. 5; and,

FIG. 7 is a cross sectional view thereof taken along 7—7 of FIG. 5.

FIG. 1

FIG. 2

FIG. 3

FIG. 4

FIG. 6

FIG. 7
